[57] CLAIM

The ornamental design for a vacuum cleaner nozzle with headlight, as shown and described.

DESCRIPTION

FIG. 1 is a front, right, top perspective view of a vacuum cleaner nozzle with headlight, showing our new design;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a bottom plan view thereof;

FIG. 8 is an enlarged front elevational view of the headlight portion thereof;

FIG. 9 is a vertical cross-sectional view of the headlight portion thereof, taken from line 9—9 of FIG. 8;

FIG. 10 is a horizontal cross-sectional view of the headlight portion thereof, taken from line 10—10 of FIG. 8;

FIG. 11 is a horizontal cross-sectional view of the headlight portion thereof, taken from line 11—11 of FIG. 8;

FIG. 12 is a horizontal cross-sectional view of the headlight portion thereof, taken from line 12—12 of FIG. 8;

FIG. 13 is a horizontal cross-sectional view of the headlight portion thereof, taken from line 13—13 of FIG. 8;

FIG. 14 is a horizontal cross-sectional view of the headlight portion thereof, taken from line 14—14 of FIG. 8;

FIG. 15 is a horizontal cross-sectional view of the headlight portion thereof, taken from line 15—15 of FIG. 8;

and,

FIG. 16 is a horizontal cross-sectional view of the headlight portion thereof, taken from line 16—16 of FIG. 8. The broken-line showing of a vacuum cleaner wand in FIG. 1 is for illustrative purposes only and forms no part of the claimed design. The headlight lens shown in FIGS. 1 and 3 is understood to be the same as the lens shown in FIG. 8.
